United States Patent Office.

JOHN SPILMAN, OF TONAWANDA, NEW YORK.

Letters Patent No. 66,532, dated July 9, 1867.

IMPROVED FLOATING WHEEL FOR VESSELS.

The Schedule referred to in these Letters Patent and making part of the same.

TO ALL WHOM IT MAY CONCERN:

Be it known that I, JOHN SPILMAN, of Tonawanda, in the county of Erie, and State of New York, have invented a certain new and useful improvement in Floating Wheels for Vessels; and I do hereby declare that the following is a full and exact description thereof, reference being had to the accompanying drawing, making part of this specification, in which—

Figure 1 is a view in elevation of my improvement attached to a vessel in the manner designed.
Figure 2 is a longitudinal section of the wheel.

Like letters designate corresponding parts in both figures.

My invention consists of an auxiliary wheel, designed to float partially immersed in the water at a suitable distance behind the vessel, being connected thereto by a rod or shaft for communicating motion to the mechanism on board, which operates the pumps or other machinery for which its use is required. The wheel is caused to rotate by the resistance of the water when it is drawn through it by the motion of the vessel, or by the force of the current when the vessel is stationary.

As represented in the drawings, A is the wheel, and B a shaft connecting it with the vessel, which may be constructed of a single rod, or coupled, as shown, or in any other suitable manner. C is a hollow cylinder, which the shaft B is attached. To this cylinder C are secured helical wings or arms E E, forming a screw, which may enter the vessel at any convenient point at the side or stern, where it is provided with suitable bearing, g, and gearing, h, or other mechanism for operating the pump.

My auxiliary wheel is more especially designed for working pumps on board of vessels employing only sails, where there is no other than manual power on board for operating the pumps in the event of the springing of a leak. As such accidents generally occur during a storm, my improvement becomes a matter of great importance, both to the safety of the lives on board, as well as of the vessel and cargo. The wheel may be of sufficient size to operate several pumps at the same time, and, since they are usually required during a storm, when the vessel is running at an increased speed, my device becomes peculiarly applicable for the purpose, as the velocity with an ordinary breeze is sufficient to render my apparatus effective, which now becomes greatly augmented. My attachment may be used, however, on board of other vessels, and to operate machinery for other purposes than for pumping, with equal advantage. When not required for use, the shaft B may be uncoupled and the wheel hoisted on board. The cylinder C being hollow and containing air renders the device sufficiently buoyant to prevent its sinking to an improper depth, although the greater the depth the greater the resistance, and consequently the power of the wheel.

What I claim as my invention, is—

The partially submerged floating wheel A, consisting of the buoyant cylinder C, helical wing or wings E E, and case f, for producing rotary motion by the resistance of the water when moved in contact therewith, substantially as and for the purposes set forth.

In witness whereof I have hereunto signed my name in the presence of two subscribing witnesses.
